UNITED STATES PATENT OFFICE

HARRY E. NORVIEL, OF ANDERSON, INDIANA, ASSIGNOR TO DELCO-REMY CORPORATION, OF DAYTON, OHIO, A CORPORATION OF DELAWARE

ELECTRIC SWITCH

Application filed November 16, 1928. Serial No. 219,903.

This invention relates to electrical switches for automobiles and particularly to switches which are adapted to be mounted adjacent the lower end of the steering column of the 5 automobile and to be operated by a shaft extending through the column and connected with a handle adjacent the hub of the steering wheel.

The present invention has been developed 10 with the aim of improving the construction and increasing the efficiency of switches of this type.

Among the several objects attained in the development of this aim, are to provide a 15 cover or enclosure for the switch assembly and terminal connections to provide for ready inspection of the terminal connections without disturbing their relative association, to provide for quickly detaching the terminal 20 connections as an assembly, to provide means for resiliently, but positively insuring correct position of the cover and connection of the terminals with their respective posts.

Other aims and objects of the present invention will be apparent from the following description, reference being had to the accompanying drawings, wherein a preferred form of embodiment of the present invention is clearly shown.

30 In the drawings:

Fig. 1 is a fragmentary side elevation of a steering column assembly to which a switch embodying the present invention in one form is attached.

35 Fig. 2 is an elevation exhibiting one form of my invention with parts broken away to show details of construction.

Fig. 3 is a view of the switch looking in the direction of the arrow 3 of Fig. 1, and having 40 the cover removed.

Fig. 4 is a sectional view on the line 4—4 of Fig. 3.

45 Figs. 5, 6 and 7 are sectional views respectively on the lines 5—5, 6—6 and 7—7 of Fig. 4.

Figs. 8 and 9 are sectional views respectively, on the lines 8—8 and 9—9 of Fig. 5.

50 Fig. 10 is a view of a modified form of my invention showing certain parts in section.

Fig. 11 is a view in elevation of a terminal assembly plate looking in the direction of the arrow 11 of Fig. 10.

Fig. 12 is a side elevation of the same plate as viewed in the direction of the arrow 12 55 in Fig. 11.

Fig. 13 is a detail view showing the assembled relation of one of the terminals, plate and switch assembly.

Fig. 14 is a sectional view substantially as 60 indicated by the line and arrows 14—14 of Fig. 3, illustrating the parts moved to a circuit closing position.

Referring to the drawings, 20 designates the mast of the steering column which is supported by the steering gear housing 21, and which provides a bearing for a steering tube 22, attached to a steering wheel 23. The tube 22 encloses a plurality of concentric tubes, the innermost of which is designated by numeral 24. The tube 24 is connected with a lever 25 located adjacent the hub of the steering wheel 23, extends through the steering column and is connected at its lower end with a switch mechanism. 70

The switch comprises a mounting cup 26 having a flat end wall 27 and a cylindrical side wall 28. The end wall 27 is struck inwardly at a plurality of points to form loops 29, with adjacent apertures 30 to receive the 75 tongues 31 about the edge of a switch enclosure member 32, as illustrated in Figs. 4 and 5. The member 32 is also provided with tangs 33 at the opposite edge thereof to be received in notches 34 in the outer edge 35 80 of a non-conducting cover plate or switch back 36, and bent over to retain the cover plate and switch parts in assembled relation. The plate 36 carries stationary switch contacts 37 which are arranged in a circular row 90 and are electrically connected with various terminal connections as posts 38 respectively.

The stationary contacts 37 are formed by the heads of inserts 39 which secure the terminal posts 38 to the plate 36, as by molding 95 the latter about the said heads. In this it is usual to mill or knurl the heads of the insets to provide a bight between them and the body of the insulating member 36, all of which is well known to those skilled in the art. These 100

contacts are adapted to be engaged by certain of a plurality of movable contacts formed by providing a somewhat triangular shaped plate 41 with spherical bosses 40. The plate 41 is supported by and is driven by a non-conducting disc 42 or contact carrier which is provided with a central opening including notches 43 for receiving tangs 44 respectively provided by the contact plate 41. A spring 45 bears at one end against the disc 42 and at the other against a detent plate 46 and thus tends to separate the parts 42 and 46 and urges the contact bosses 40 into engagement with the plate 36 or the stationary contact 15 and urges the spherical bosses 47 provided by the plate 46 toward the end wall 31 of the switch case or mounting cup. The end wall 31 is provided with holes 48 arranged in a circular row and each adapted to receive one of the spherical bosses 47. The contact carrying disc 42 is drivingly connected with the detent plate 46 by providing the latter with tangs 49, which are received by notches 50 provided by the contact carrier 42.

Both the contact carrier 42 and the detent plate 46 are driven through the tangs 49 by a disc 51 having notches 52 for receiving the tangs 49 and provided with a central opening 53 for receiving the shaft 24 and provided with a key 54 which is received by a suitable longitudinal groove in the tube 24.

The spring 45 performs the dual function of maintaining the movable contacts in engagement with the stationary contacts and maintaining the detent bosses 47 in engagement with the holes 48 of the plate 41, so that the movable contact will be yieldingly retained in various operating positions into which it is moved by the lever 25.

Motion of the movable contact is limited by providing the plate 46 with an arcuate notch 55 which receives a lug 56 integral with the case wall 31. The parts 57 and 58 defining the notch 55 serve as stops engageable with the lug 56 in order to limit movement of the plate 46 in either direction.

The switch case is fixed to the lower end of the steering gear case 21 by a mounting plate 60 attached to the mounting cup 26, and having a slot 61 for receiving the stud 63 attached to the steering gear case 21. The slot 61 permits adjusting the cup 30 angularly relative to the shaft 24, so that the switch may be located properly with respect to the switch operating handle 25.

As is shown in Figs. 2, 3, 4, and 10, the supporting cup 26 is somewhat larger than the switch inclosure 32, and when in assembled relation therewith, provides an annular channel 62 between the cup side wall 28 and the member 32. This channel 62 is used to house the meeting end or flange 63 of a cover member 64, disposed about the end of the switch assembly, and which is provided with quickly detachable means to secure the cover

to the cup as by means of the bayonet and slot connections illustrated in the drawings, and generally indicated by the numeral 65. To insure proper retention of the cover to the case, once it has been fixed by the securing means 65, resilient means are provided, as by the spring 66, for engaging a part of the cover and assembly to keep them in their associated relation.

In one form of my invention, that illustrated in Figs. 1 to 4 inclusive, I accomplish this by providing the spring 66 in the form of a circular ring of spring wire of a size that must be compressed slightly to be placed within the cup 26, at which time it will expand sufficiently to lie adjacent the side wall 28 of the cup, and I further provide the ring with reverse lateral bends or bights 67 of sufficient magnitude such that when placed within the cup 26, that each alternate bend 85 will engage the wall 27 of the cup as at 68, while the intervening and oppositely disposed bends will engage the edge of the cover 64 as at 69, when the cover is being connected with the mounting cup, and be compressed 90 somewhat during the passing of the cover into locking engagement with the cup.

The supporting cup 26 and cover 64 are so designed that they will completely enclose the switch assembly and all of its appertinent connections, and in view of this, the body thereof is of ample size to provide a chamber 70 for the disposition of electric wire or terminal leads 71 with their connectors 72 in their relation with the posts 38. 100 In one form of my invention, this connection is accomplished by means of screws 73 passing through apertured ears of the connectors 72, and threaded into the end of the posts 38. The cover 64 is provided with a convenient 105 opening 74 to allow passage of the leads 71 to the exterior of the case and thence be distributed to their respective points of connection.

In a second form of the invention, the 110 cover member 64a takes the form of a sleeve member having the flange 63 prolonged backwardly to a point where an annular ridge or shoulder 75 is formed circumferentially thereof for an abutment purpose, later to be 115 described, and thence tapers to the centrally disposed aperture 74a, through which the leads 71, which may be formulated into a unitary cable 76, are threaded. In this instance, the leads 71 terminate in connectors 120 72a of the quick detachable type, and comprise a pin-like tip fixed to the bared end of the lead 71 by means of the bore 77 being received thereon. The free end of the connector is provided with a reduced portion 125 to be received by the central bore of the post 38, and intermediate the ends of the connector 72 there is provided an annular flange 78 providing a shoulder on each side thereof as it joins the respective end portion. By 130

means of the reduced end of the connector 72a being telescopically received by the post 38, a readily detachable connection is provided between the leads and the switch assembly.

Means are provided for keeping the connectors 72a in good contact and in proper relation with their respective posts 38, in the form of a terminal assembly plate 79. The 10 plate 79 is of non-conducting material and of a form and size to be contained within the cover 64. The plate is provided with notches 80 in the edge thereof and terminating in substantially pear shaped or enlarged apertures 81. These apertures 81 are oriented about the surface of the plate to be disposed over the posts 38, and are of a size to nicely receive the larger portion of the connector 72a, but to prevent the connector passing out through 20 the notch 80, or the flange 78 passing through the aperture 80. Fixed to one side of the plate, the spring 66a is embodied in a strip 25 of resilient material of sufficient length to be received at its ends 83 by the shoulder 75 of the cover 64, earlier referred to.

In assembling the plate 79 with the connectors, the flexible part 84 of the leads 71 are passed inwardly through the respective notches 80 to the enlarged portions or apertures 81, and then the leads 71 are drawn backwardly through the apertures 81 until the connectors 72a are received within the apertures 81, and the flange 78 is engaged by the plate 79, the shoulder of the ridge seating against the edge portion of the aperture 81, as indicated at 85 in Fig. 13. The posts 38 and their cooperating connectors 71 are so disposed about the switch assembly that there is but one position in which they can be assembled, and in the present instance that form is illustrated by the positioning of the apertures 81, in Fig. 11. This feature provides a readily detachable connection of the switch assembly and terminal leads and insures proper connections of the respective parts when re-assembled, for the terminal assembly plate 79 with the leads 71 positioned in their proper apertures 81 are in the exact form to be received as a unit by the similarly positioned posts 38, when the plate with its assembly of connectors 72a is brought into contact with the switch assembly.

After the connectors 72a have been inserted within the recesses of the posts 38, the cover 64a, being threaded with the leads 71 or the cable 76, is then passed over the terminal plate and assembled connections until the shoulder 75 engages the ends 83 of the spring 82, compressing or flexing it, until the flange 63 of the cover 64 is received by the locking or retaining means 65, earlier referred to. In this embodiment of my invention, the spring 82 performs the dual function of maintaining the cover 64 in locked or retained engagement with the supporting cup 26, and

also forces the plate 79 against the shoulders of the connectors 72, forcing them into good electrical contact with the posts 38. However, upon removal of the cover 64 the tension of the spring 82 is released and the terminal 70 plate 79 with the attached connectors 72 may be readily removed.

As a protection of the switch mechanism within the enclosure against deteriorating effects due to the change in weather conditions, and to exclude moisture from the interior of the casing, a dry felt washer or gasket 90 is inserted between the end wall 27 of the cup 26, and the attaching or mounting plate 60, when these parts are assembled. 75 The gasket 90 takes up the oil from the switch housing and thereby provides a barrier against the passage of water into the casing around the tube 24, and also provides an anti-rattling connection between the parts absorbing all vibration that might otherwise occur.

While the form of embodiment of the present invention as herein disclosed, constitutes a preferred form, it is to be understood 90 that other forms might be adopted, all coming within the scope of the claims which follow.

What is claimed is as follows:

1. In an electric switch, the combination 95 comprising a mounting cup and bracket, a switch assembly within the cup including a switch back provided with terminal posts, leads connected to the posts, a cover cooperating with the mounting cup to enclose the 100 switch assembly and leads, and means to resiliently secure the cover to the said cup member.

2. In an electric switch, the combination comprising a mounting cup, a switch assembly within the cup, terminal posts carried by one wall of the assembly, leads connected to the posts, a cover for said terminals and assembly, having locking engagement with the cup, and spring means urging the cover and 110 cup in locked relation.

3. In an electric switch, the combination comprising a mounting cup, a switch assembly within the cup, terminal posts carried by one wall of the assembly, leads connected to the posts, a cover for said terminals and assembly, having locking engagement with the cup, and spring means engaging the cover and maintaining the locking engagement of 115 said cover cup.

4. In an electric switch, the combination comprising a mounting cup, a switch assembly within the cup, terminal posts carried by one wall of the assembly, leads connected to the posts, a cover for said terminals and assembly, having locking engagement with the cup, and spring means within the cup and engaging the cover to maintain the locking 125 relation of cover and cup.

5. In an electric switch, the combination 130

comprising a mounting cup, a switch assembly within the cup, one wall of said assembly forming a contact support provided with terminal posts, leads connected to the posts and a cover resiliently supported by the cup enclosing said assembly and terminal connections.

6. In an electric switch, the combination comprising a mounting cup, a switch assembly within the cup, terminal posts carried by one wall of the assembly, leads connected to the posts, a cover telescopically received by the cup for enclosing the assembly and leads, and means resiliently maintaining the cover in enclosing relation.

7. In an electric switch, the combination comprising a mounting cup, a switch assembly within the cup, terminal posts carried by one wall of the assembly, leads detachably connected to the posts, a terminal assembly plate supporting the leads in cooperative relation to the posts, and a resiliently supported cover engaging the cup, to enclose the assembly and terminal connections.

8. In an electric switch, the combination comprising a mounting cup, a switch assembly within the cup, terminal posts carried by one wall of the assembly, leads detachably connected to the posts, a terminal assembly plate supporting the leads in cooperative relation to the posts, a cover enclosing the switch assembly and terminal connections thereto, and means within the cover maintaining the enclosed relation.

9. In an electric switch, the combination comprising a mounting cup, a switch assembly within the cup, terminal posts carried by one wall of the assembly, leads detachably connected to the posts, a terminal assembly plate supporting the leads in cooperative relation to the posts, a cover enclosing the switch assembly and terminal connections thereto, and means within the cover maintaining the enclosed relation and securing the terminal assembly plate in position.

10. In an electric switch, the combination comprising, a mounting cup, a switch assembly within the cup, terminal posts carried by one wall of the assembly, leads detachably connected to the posts, a terminal assembly plate disposed adjacent the posts and supporting the leads in contacting relation to the posts, and a cover engaging the cup to enclose the switch assembly and terminal connections.

11. In an electric switch, the combination comprising; a mounting cup, a switch assembly within the cup, terminal posts carried by one wall of the assembly, leads detachably connected to the posts, a terminal assembly plate disposed adjacent the posts and supporting the leads in contacting relation to the posts, a cover engaging the cup to enclose the switch assembly and terminal connections, and means carried by said plate to insure

retention of the cover and maintain contacting relation between the leads and posts.

12. In an electric switch, the combination comprising, a mounting cup, a switch assembly within the cup, terminal posts carried by one wall of the assembly, leads detachably connected to the posts, a terminal assembly plate disposed adjacent the posts and supporting the leads in contacting relation to the posts, a cover engaging the cup to enclose the switch assembly and terminal connections, and a spring engaging said plate and cover to retain both cover and plate in position.

13. In an electric switch the combination comprising, a mounting member, a switch assembly carried by the member and providing terminal posts, leads detachably connected to the posts, a terminal assembly plate supporting the leads in their relative positions, a cover detachably connected to the mounting member and providing a closure for the switch assembly and terminal connections, and means disposed between the cover and plate to maintain the cover and plate in proper position.

14. An electric switch adapted to be mounted at the lower end of a steering column and having provisions for control through the said steering column, comprising in combination, a contact carrier, a detent plate coaxially rotatable with the carrier and drivingly connected thereto, a case enclosing the carrier and plate, stationary contacts carried by a wall of the case and engageable with a movable contact on said carrier, means interposed between the contact carrier and detent plate for insuring relative cooperation of said contacts and detent, a mounting cup providing a support for said case, and a cover for the switch assembly releasably engaging the mounting cup.

15. An electric switch comprising in combination, a mounting cup provided with a bracket by which it is supported, a switch housing mounted in the cup, a switch back closing the housing and providing a number of contact terminals exterior of the same, a lead assembly including tip members for mating engagement with said contact terminals, and a spacing plate loosely receiving the tip members and holding them for simultaneous engagement with their respective contact terminals, a cover mating with said mounting cup and enclosing said spacing plate and switch structure, and means resiliently connecting the cover and plates whereby the cover and cup will be retained in mating relation and the tip members in electrical engagement to the contact terminals.

16. A switch of the character described comprising, a mounting cup secured to the switch housing, a lead assembly provided with tip members for proper engagement with terminal posts carried by the switch housing, a cover enclosing the demountable connection

and mating with the mounting cup to provide a weather tight enclosure, means resiliently connecting the cover with the spacing plate, whereby firm engagement of the parts
5 is assured.

17. In a switch of the class described in the combination comprising a switch housing providing contact terminals exterior thereof, a detachable lead assembly, a spacing plate
10 receiving each of the leads and maintaining them in position to engage their respective terminal members, cover means enclosing the switch and terminal assembly, means operable from a portion of said cover means to
15 maintain the spacing plate in position.

18. A switch of the character described comprising in combination, a mounting cup having a bracket by which the structure is supported, switch mechanism mounted with-
20 in a case and secured centrally of the mount-
ing cup, means operable through the bottom of the cup to operate the switch device, a spring ring disposed within the cup about the switch housing, leads attached to the
25 switch mechanism, and a cover mating with the mounting cup to enclose the lead connec-
tion with the switch device, said spring ring engaging the cover and operable to maintain latching engagement with the mounting cup.

19. In a switch of the character described the combination comprising, a storm proof enclosure comprising a mounting cup wherein the switching device is mounted, a cover having bayonet and slotted engagement with
25 the mounting cup and enclosing the switch-
ing device and the junction of the terminal leads attached thereto, and means resiliently engaging the cover to maintain latching en-
gagement with said mounting cup.

20. In testimony whereof I hereto affix my sig-
nature.

HARRY E. NORVIEL.
